CLAIM

We claim the ornamental design for a loudspeaker, as shown and described.

DESCRIPTION

FIG. 1 is a front, top, right perspective view of a loudspeaker according to the present invention;

FIG. 2 is a rear, top, right perspective view thereof;

FIG. 3 is a right side elevation view thereof;

FIG. 4 is a left side elevation view thereof;

FIG. 5 is a front elevation view thereof;

FIG. 6 is a rear elevation view thereof;

FIG. 7 is a top plan view thereof; and,

FIG. 8 is a bottom view thereof.

The dashed broken lines immediately adjacent the shaded areas represent the bounds of the claimed design while all other broken lines are included for the purpose of illustrating portions of the loudspeaker; the broken lines form no part of the claimed design.
